FUSED ELECTRIC MULTIPLE RECEPTACLE

Seymour Robinson, Miami, Fla., assignor to Stanley M. Richardson, D.D.S., Miami Beach, Fla.

Filed June 12, 1968, Ser. No. 12,308

Term of patent 14 years

Int. Cl. D13—03

U.S. Cl. D26—1

FIG. 1

FIG. 2

FIG. 3

FIG. 4

FIG. 5

FIG. 1 is a front elevation of a fused electric multiple receptacle showing my new design.

FIG. 2 is a rear elevation thereof.

FIG. 3 is a side elevation thereof.

FIG. 4 is a top plan view thereof.

FIG. 5 is a bottom plan view thereof.

The side not shown is the same as that shown in FIG. 3. The dotted lines are for illustrative purposes only.

I claim:

The ornamental design for a fused electric multiple receptacle, as shown and described.
